COMBINED ADVERTISING CARD AND MAILER FOR CURRENCY, ETC

Filed Dec. 11, 1928

UNITED STATES PATENT OFFICE

WALTER W. F. TEES, OF BROOKLYN, NEW YORK

COMBINED ADVERTISING CARD AND MAILER FOR CURRENCY, ETC.

Application filed December 11, 1928. Serial No. 325,312.

This invention relates to an improved mailing card or device, which may be economically constructed and used by advertisers or others, and which may be used as a direct mailing card or inserted into a standard size envelope, for the purpose of carrying small articles, such as samples, coins, stamps, bills, and the like.

The primary object of this invention is the provision of a mailing card having a flexible envelope attached thereto in a novel, economical, and efficient relation, and by means of which currency, tickets, samples, and other small articles may be carried with ease and facility, and in a manner which will insure their retention; the envelope covering but a small portion of the card and leaving the other portion of the card free for mailing or reference data.

Other objects and advantages of the invention will be apparent during the course of the following detailed description.

In the accompanying drawing, forming a part of this specification, and wherein similar reference characters designate corresponding parts throughout the several views,

Figure 1 is a front elevation of the improved mailing card, showing the envelope attached to the card with its closure flap open ready to receive an article therein for mailing.

Figure 2 is a fragmentary view of the card, showing the envelope attached end thereof, at the rear of the card.

Figures 3 and 4 are sectional views taken substantially on their respective lines in Figure 1 of the drawing.

Figure 5 is a view of the inside surfaces of the blank from which the envelope is formed, showing it in the relation in which it is made or attached to a mailing card.

In the drawing, wherein for the purpose of illustration is shown only a preferred embodiment of this invention, the improved device A may consist of the card body 10, which is preferably only slightly flexible, being constructed of heavy cardboard, so that it will not bend readily, obviously, for the reason that the envelope 11 for attach-

ment thereto must be maintained in a flat condition to prevent accidental displacement or destruction of the article contained therein. The card body 10 is of horizontally elongated construction, rectangular in form, and of a size to fit a standard envelope. On one end thereof it is entirely blank, for receiving the envelope 11 in attached relation thereon; this envelope 11 covering slightly less than one-half of the horizontal length of the mailing card. On the exposed portion of the card 10, laterally of the envelope, on one or both faces, thereof, the blank spaces, or other indicia 15 may be disposed thereon in appropriate designation of the name of the sender; the name of the receiver; and spaces or lines for remarks, if desired. The card is such that it may be readily filed and used as a reference card for solicitation, from which a mailing list may be compiled and maintained.

Referring to the envelope 11, shown in blank form in Figure 2 of the drawing, the same is preferably stamped or cut from a single sheet of material, preferably strong but economical stock. It comprises a body flap 12 of rectangular form, having the side attaching flanges 13 and 14 secured thereto. A back flap 15, preferably slightly narrower than the body flap 12 is secured along a folding line 17 to the body flap 12. A closure flap 18 is secured along a fold line 19 to the end of the back flap 15, opposite the body flap 12. The attaching flaps 13 and 14 are relatively narrow and the attaching flap 13 extends for substantially the entire length of the body flap 12, being diagonally cut at 21 from the fold line 17, at an angle of about 45° in the direction of the attaching flap 13, to facilitate folding without bulk. The body flap 12 at its inserting end of the envelope is concavely cut at 23. The attaching flap 14 is of about the same width as the flap 13, and extends from the free edge of the body flap 12 to a location short of the folding line 17, where the said attaching flap 14 terminates at 25. From the location 25 the body flap 12 is diagonally cut at 26 from the fold line of the flap 14 to a

location intersecting the fold line 17, a short distance inwardly of the fold line 28 of the flap 14, as can be seen from Figure 5 of the drawing. This is for the purpose of facilitating opening of the envelope with a paper cutter, to remove the contents of the envelope, as will be subsequently described. Thus, it is obvious that the corner of the body flap 12, at the location 26, is 10 cut away. The back flap 15 is of less width than the body flap 12; having one side edge 30 thereof aligned with the fold line 31 of the attaching flap 13. The other edge 32 of the back flap 15 extends parallel with the fold line 28 of the adjacent attaching flap 14 of the body, extending from the location where the sloping cut lines 26 intersect the fold lines 17, and terminates at a transverse cutting line 33 just short of 20 and parallel with the fold line 19 of the closure flap 18. Thus, the back flap 15 has a rectangular section cut from the side thereof. At its outer portion the back flap 15, between the line 33 and the fold line 19, 25 is of the same width as the body flap 12.

The attaching flap 13; the back flap 15; and the closure flap 18 are all gummed, preferably entirely thereover, on the same side of the blank. The attaching flap 14, on the other hand, is gummed on the reverse side of the blank from the aforementioned flaps. The body flap 12, of course, is not gummed on either side. This gumming material is designated by the stippling in Figure 5 and by the dot and dash cross sections in Figures 3 and 4 of the drawing, and it may be of any nature suitable to adhere when moistened.

Referring to the attachment of the envelope upon the card, it is to be noted that the body flap 12, as well as the rear flap 15, are each of substantially the same height as the card body 10. The rear flap 15 is moistened on its gummed surface and attached on the rear of the card body 10, at the end to which the envelope is to be attached, in such relation that the side edge 30 of this flap is substantially parallel and flush with the end edge of the card body 10. The folding edge 19 of the closure flap 12 is located substantially flush with the top edge of the card body 10, so that the closure flap extends above the top margin 40 of the card body 10, as shown in Figure 1 of the drawing. The attaching flap 14 is then bent upon its fold line 28 inwardly upon the inner surface of the body flap 12 of the envelope, and moistened on its gummed surface, and the body flap 12 is then bent to overlie the front surface of the card body 10, and the gummed surface of the attaching flap 14 adheres to the front of the card body 10, as shown in Figure 3 of the drawing. The attaching flap 13 is of course moistened on its gummed surface and bent

on its fold line to rearwardly overlie the card body 10 and the already pasted back flap 15, being secured over the latter, as shown in Figure 2. This position of parts is shown in Figures 1 and 2 of the drawing, and elsewhere, and it is to be noted that the cut-away portion at the top of the body flap enables the insertion of a finger or an instrument so that the article to be slipped into the envelope may be readily entered 70 between the body flap and the card 10. Due to the cutting of the lower right hand corner of the body flap, at the line 26, it is to be noted that the said lower right hand corner of the envelope, when secured on the 80 card 10, presents a slight opening for the admission of an instrument, such as a paper cutter, by means of which the envelope may be readily opened to remove the article which has been inserted therein. This feature may or may not be a part of the improved mailing card.

The manner in which articles are inserted and mailed will be obvious. They are slipped between the body flap 12 and the 90 card 10, within the envelope, and the closure flap is of course moistened on its gummed surface, and bent on its fold line to overlie the envelope body flap and it is pasted there-to for closing the envelope.

It is apparent from the foregoing that an improved envelope-mailing card has been provided, which may be used as a postal mailing card or fitted into a standard envelope for conveniently and efficiently carrying samples, currency, tickets, novelties, and other articles. The application of the envelope blank to the stiff cardboard body is practical, and may be economically accomplished by means of suitable machinery.

Various changes in the shape, size, and arrangement of parts may be made to the form of invention herein shown and described, without departing from the spirit of the invention or the scope of the claims.

I claim:

1. In an envelope blank for mailing cards the combination of a flexible envelope blank sheet comprising back and body flaps, the body flap having side attaching flaps and the back flap having an end closure flap opposite the body flap, the attaching flaps of the body flap being provided with gummed surfaces on relatively opposite sides thereof, and the back and closure flaps having gummed surfaces on the inner sides thereof.

2. In a mailing card the combination of a horizontally elongated card-like body having at one end thereof an envelope comprising a body flap provided with a back attaching flap folded under the lower margin of the card and adhered to the rear of the card, the body flap having side attaching flaps, one side flap of which is folded about the end margin of the card and adhered to

the rear of the card, and the other side attaching flap of which is folded beneath the body flap and adhered to the facing side of the card body, and a closure flap secured to the card body and extending above the top margin thereof for folding over upon the body flap to close a pocket between the body flap and card body.

3. In a mailing card the combination of a horizontally elongated card-like body having at one end thereof an envelope comprising a body flap provided with a back attaching flap folded under the lower margin of the card and adhered to the rear of the card, the body flap having side attaching flaps, one side flap of which is folded about the end margin of the card and adhered to the rear of the card, the other side attaching flap of which is folded beneath the body flap and adhered to the facing side of the card body, a closure flap secured to the card body and extending above the top margin thereof for folding over upon the body flap to close a pocket between the body flap and card body, the lower corner of the body flap of the envelope being removed to provide a small opening sufficient to insert a paper cutter for ripping open the envelope upon the card body when the closure flap is sealed.

4. In a device of the class described a stiff cardboard body having appropriate designations on a portion thereof and on the other portion being provided with an article inserting envelope comprising a body flap over the front of said portion of said card body, the body flap of the envelope having side attaching flaps, one of which is bent beneath the body flap of the envelope and secured to the card-like body and the other attaching flap of which is bent about an end of the card and secured in a gummed relation to the rear of the card-like body, said body flap having a foldable back flap at the lower edge thereof folded about the lower edge of the card body and provided with a gummed surface adhered to the back of the card body, the back flap having a closure flap secured on a fold line and projecting above the top of the card body in relation to be secured over the body flap of the envelope to close said envelope.

WALTER TEES.
